WINDOW CONSTRUCTION

Joseph Schunk, Newark, N. J., assignor to The
National Lock Washer Company, Newark,
N. J.

Application November 4, 1939, Serial No. 302,811

2 Claims. (Cl. 189—72)

This invention relates to improvements in window construction especially adapted for use on cars and buses.

In cars and buses the windows are usually constructed so that they can be raised and lowered and held to one or more heights above the windowsill. With such a construction, it is the practice to have a spring maintain engagement between the lock rack and the sash lock bolt, the arrangement being such that the sash may be raised without operating the sash lock lever. This is in order that the window may be raised and the sash lock will automatically engage with notches in the window guide rack. In such a construction, the end of the lock bolt drags along on the face of the rack, with the result that the rack face engaged by the end of the bolt becomes worn and roughened, which worn and roughened surface will catch into the weather strip usually used on the edge of the window sash, thereby making it difficult to operate the window. In my Patent 2,177,463, issued October 24, 1939, I have shown and described a construction which obviates to a great extent the difficulties mentioned.

It is an object of my present invention, however, to provide a more simplified and cheaper arrangement, and my improved form of construction is shown in the annexed drawing, wherein:

Figure 1 is a partial cross-sectional view through a part of the window where the window sash engages a side member of the window frame.

Figure 2 is a partial front elevational view of Figure 1.

Figure 3 is a view on the line 3—3 of Figure 2.

Figure 4 is a view on the line 4—4 of Figure 3.

Figure 5 is a fragmentary perspective view of an end or section through the sash guide member.

Figure 6 is a perspective view of a portion of the lock bolt rack showing one of the notches 40 with the lock bolt shown in dotted position.

Figure 7 is a perspective view of one of the removable sides of the guide member shown in Figure 5.

Figure 8 is a modified form of construction of the upper portion of the construction shown in Figure 4.

Figure 9 is a sectional view through the sash guide member, the lock bar being shown in dotted position.

Figure 10 is a view similar to Figure 9, but a modified form of construction.

In the different views wherein like numbers refer to corresponding parts, 1 is a fragmentary portion of the vertical post of a window frame to 55 which is fastened, as by screws 3 and 4 (see Fig-

ure 4) a guide member 2. The guide member 2 has grooves 5 and 6 therein to reduce the weight and cost of the strip. The guide member 2 has a seat portion or surface 7, from the opposite sides of which extend sides 8 and 9, one of which, for example the side 9, is removably carried by the guide member 2 for the purpose of assembling the window sash into the guide member. The side member 9 is held in place by any satisfactory means such as one or more screws 10.

Between the side members 8 and 9, is positioned a U-shaped sash member 11 which is adapted to receive a glass pane 12, the same being held in the sash member 11 by a suitable sizing strip 13. Also fastened to the sash member 11 in any satisfactory manner as by a suitable cement, is a weather strip 14 made of felt or other suitable material, which will slide between the sides 8 and 9 of the guide member 2. The guide member 2 is provided with a channel 15 which intercepts the surface or seat 7. Positioned within the channel 15 is a rack 16 having a plurality of notches 17 to receive the end 18 of a lock bolt 19. The lock bolt 19 is adapted to be operated by a lever 20 pivotally mounted through a member 21 on a window sash member 22. Since the lock bolt per se forms no part of my present invention, no further description appears to be necessary.

The rack 16 as shown in Figure 4 is held from moving longitudinally of its length by the screw 3 and terminates at a point adjacent the screw 4. However, as shown in Figure 8, the rack 16 may extend so as to be engaged by the screw 4.

As shown in Figure 9, the rack 16 is dove-tailed in cross-section and fits a corresponding formation in the guide member 2 so that all lateral displacement is prevented. However, the formation may be rectangular in shape as shown in Figure 10. In either construction, the guide member 2 is made of extruded material, preferably aluminum or aluminum alloy, and the rack may also be of extruded material or rolled material, but of a harder consistency than that of the guide member 2; for example, it may be of steel or hard rolled brass or bronze, or an alloy of steel. As shown particularly in Figures 9 and 10, the rack 16 is positioned below the surface or seat 7, and the end 18 of the lock bolt fits within the channel and engages the rack 16 without coming in contact with the seat 7 which is engaged by the weather strip 14.

While I have utilized, as indicated in Figure 4, the screw 3 which holds the guide member 2 of the window frame member 1, to hold the rack 16 in position within the channel of the guide mem-

ber, this is not necessary as the guide member in both forms shown in Figures 9 and 10 may be easily and quickly staked into position so that no screws, rivets or welding, such as utilized in my 5 patent previously referred to, is required. This construction, as heretofore pointed out, materially reduces the cost of manufacture of structures of this kind.

With this construction, the surface on which 10 the weather strip 14 runs is kept smooth and the rack 16, being made of harder material, reduces the wear between it and the lock bolt so that a much smoother operating window construction is obtained.

15 What I claim is:

1. In a window construction including a sash having a member carrying a lock bolt, a guide member with means for fastening it to a window frame member, said guide member having a relatively thick base portion with a seat and spaced sides extending inwardly toward the window sash from the base portion and seat, one of said sides being removably carried by the guide member, a sash member for receiving a glass pane and carrying a weather strip to move with it between said sides and against said seat, the guide member having a longitudinal channel directly in the base portion, the channel being positioned toward

the window frame member from the seat, and a rack member having lock notches therein and of harder material than the seat portion of the guide member and securely positioned in the channel and substantially filling the channel except at the plane of the seat to receive the end of the sash lock bolt. 5

2. In a window construction including a sash having a member carrying a lock bolt, an extruded guide member with means for fastening it 10 to a window frame member, said guide member having a seat and spaced sides extending inwardly toward the window sash from the seat, one of said sides being removably carried by the guide member, a sash member for receiving a 15 glass pane and carrying a weather strip to move with it between said sides and against said seat, the guide member having a longitudinal channel, dove-tail in cross-section, positioned toward the window frame member from the seat, and a rack 20 member having lock notches therein and of harder material than at least the seat portion of the guide member fitting the dove-tail-shaped channel to receive the end of the sash lock bolt, the inner edge of the rack member being located 25 below the plane of the seat.

JOSEPH SCHUNK.
